WATER HEATING SYSTEM

Clark M. Osterheld, Stoughton, Wis., assignor to
McGraw Electric Company, Elgin, Ill., a corporation of Delaware

Application March 31, 1941, Serial No. 385,975

5 Claims. (Cl. 219—39)

My invention relates to control systems and particularly to control systems for hot water heaters.

An object of my invention is to provide a system of control for the heater of a hot water tank including switching means effective to cause energization of the heater at any time during the day when the tank is less than full of hot water, this condition continuing during times of ordinary loads, and that will be effective to continue energization during periods of heavy loads on other circuits than the heater circuit only in case less than a predetermined fractional part of the water content of the tank is hot.

Other objects of my invention will either be apparent from a description of one form of system embodying my invention or will be set forth in the course of such description and particularly in the appended claims.

In the single figure I have illustrated, generally only, a domestic hot water tank having associated therewith my improved heating control system.

I have shown a hot water tank 11 which is provided with a cold water inlet pipe and a hot water outlet pipe and which is to be understood as being substantially of the construction now well known in this art.

I provide preferably a single heater 13 and I provide a pair of thermally actuatable heater control switches 15 and 17 so mounted on the tank as to be subject to water temperature at two different points on the tank. The switch 15 is connected in series circuit relation to heater 13 and I have shown a flexing bimetal bar 19 for the lower switch 15 which is adapted normally to be in electrical engagement with a fixed contact member 21 as long as less than substantially all of the water in the tank is hot but is adapted to move out of engagement with fixed contact 21 when substantially all of the water in the tank is hot.

The upper thermal switch 17 includes a flexing bimetal bar 23 and a fixed contact member 25 and it is to be understood that the two thermal switches 15 and 17 are adapted to be in close heat receiving engagement with the tank 11. It is evident that the amount of hot water affecting the upper thermal switch 17 will vary with the position of this switch relatively to the height of the tank, all as will be hereinafter set forth.

I provide an electromagnetically actuatable switching means 27 embodying a plurality of contact members and adapted to be moved selectively to a plurality of different operating positions. I provide a pair of spaced fixed contact

members 29 and 31 and a contact arm 33 normally yieldingly biased into engagement with fixed contact member 31 but adapted to be moved out of engagement therewith and into engagement with fixed contact member 29 by an electromagnet including a coil 35 and a fixed magnetizable core 37 which core 37 is adapted to magnetically energize an armature 39 mounted on the outer end of contact arm 33. Fixed contact member 31 is connected by a conductor 41 with fixed contact member 21 while contact 29 is connected through a conductor 43 with fixed contact member 25 of the upper thermal switch 17. Contact arm 33 is connected through a conductor 45 with one supply circuit conductor 47.

I have shown a pair of supply circuit conductors 47 and 49 as being connected through suitable fuses 51 with two bus bars 53 and 55 mounted on a suitable panel board 57, all in a manner well known in the art. I have illustrated the use of fuses 53, one of which is connected in circuit with conductor 45 and the other of which is connected in circuit with a conductor 61 having one end thereof connected with one terminal of heater 13 and the other end thereof with bus bar 53. The other terminal of heater 13 is connected with the fixed support of bimetal bar 19. I connect the fixed supports of bimetal bars 19 and 23 by a conductor 63.

Since I desire to change the operative position of switching means 27 at and during the times of excess load in a predetermined circuit other than the heater circuit of tank 11, I connect coil 35 in series electric circuit with the conductors 65 and 67. Conductor 67 is connected to bus bar 55 through a suitable fuse and I have shown a plurality of incandescent lamps 69, a motor 71 and a plurality of resistors 73 as connected to the other circuit including conductors 65 and 67. Thus the lights 69 might represent a house lighting load, suitable provision being made to separate the lighting circuit from all of the other circuits. The motor 71 might be considered to represent the motor of an oil burner, the motor of a refrigerator, or that of a fan motor, it being understood that this is representative only. The resistors 73 may be considered, for instance, to represent a range load and in order to indicate that the amount of current in this other electric load circuit is variable, I have illustrated the use of a manually operable switch as applied to and connected in circuit with the individual appliance mentioned above. Conductor 65 is connected to one terminal of coil 35, the other termi-

nal of which is connected by a conductor 75 with the other bus bar 53.

Reference to the single figure of the drawing will show that as long as the load in a second load circuit is below a predetermined value, contact arm 33 of switch 27 is in engagement with fixed contact member 31 and heater 13 will be energized during all such time in case less than all of the water in the tank is hot through a circuit substantially as follows: From supply circuit conductor 49 through conductor 61, heater 13, through closed thermal switch 15, through conductor 41 to contact 31, through contact arm 33 and conductor 45 to bus bar 55 and from there to the other supply circuit conductor 47. It is therefore evident that if less than all or substantially less than all of the water in the tank is hot, heater 13 will be energized during all such periods of the day when the value of the current in the other circuit is less than a predetermined amount.

Let it be assumed, for instance, that the other circuit is one including the range heaters and that it is desired to cause deenergization of the heater 13 of the tank in case at least a predetermined fractional part of the water content of the tank is hot at the time when the current in said other circuit, traversing the resistors 73, is beyond or above a certain value. When the current through coil 35 in said other circuit is beyond said predetermined limit or value, the contact arm 33 will be moved so that it is in engagement with fixed contact 29 whereby another circuit through the heater 13 will be energized provided certain other operating conditions are present. This circuit is substantially as follows: from supply circuit conductor 49 to bus bar 53, through conductor 61 and heater 13, through conductor 63, through the upper thermal switch 17, (if subject to cold water) through conductor 43 to contact 29, to engaged contact arm 33 and from there through conductor 45 to bus bar 55 and from there to the other supply circuit conductor 47. The operating conditions necessarily present in case the above described energizing circuit is effected by the switching means are that less than a predetermined fractional part of the water content of the tank is hot with the result that upper thermal switch 17 is subject to the temperature of cold water. The above described operation of my improved system is therefore such that the heater 13 will be energized even during periods of relatively heavy load on another circuit in, say, the house if the amount of hot water in the tank is not sufficient for ordinary requirements, but if the upper thermal switch 17 is responsive to the temperature of hot water, that is, the tank contains a sufficient amount of hot water to meet ordinary running requirements, the heater 13 will not be energized during periods of heavy load on another circuit in the house irrespective of when such periods of heavy load occur.

Various modifications may be made in the system embodying my invention as herein shown and described and all such modifications clearly coming within the scope of the appended claims are to be considered as being covered thereby.

I claim as my invention:

1. A water heating system for a hot water tank comprising an electric circuit having an electric heater for the tank connected therein, a thermally-responsive switch subject to tank water temperature at an upper part of the tank, a heater-control switch comprising a pair of fixed

contacts, a contact arm selectively movable into engagement with said fixed contacts and normally yieldingly biased into engagement with one of said fixed contacts to cause energization of said heater in case less than all of the water in the tank is hot, a second electric load circuit and means controlled by the current in said second circuit when the current therein exceeds a predetermined value for causing movement of said contact arm into engagement with the other contact to continue energization of the heater in case said thermally-responsive switch is subject to cold water.

2. A water heating system for a hot water tank comprising an electric circuit having an electric heater for the tank connected therein, heater-control switching means normally biased into position to effect energization of said heater in case less than all of the water in the tank is hot, a second electric load circuit, and electromagnetic means controlled by an excess load current in said second circuit for continuing energization of said heater if less than a predetermined fractional part of the water in the tank is hot.

3. A water heating system for a hot water tank comprising an electric circuit having an electric heater for the tank connected therein, heater-control switching means normally biased into position to effect energization of said heater in case less than all of the water in the tank is hot, a second electric load circuit, and electromagnetic means controlled by an excess load current in said second circuit to interrupt the heating circuit of said heater on occurrence of an excess load current in said second circuit when more than a predetermined fractional part of the water in the tank is hot and for continuing energization of said heater if less than said predetermined fractional part of the water in the tank is hot, said energization continuing, under said second circuit overload conditions, until said predetermined fractional part of the water in the tank is hot and continuing, under normal load conditions, until substantially all of the water in the tank is hot.

4. A water heating system for a hot water tank comprising an electric circuit having an electric heater for the tank connected therein, a main thermally-actuable heater control switch for deenergizing said heater when substantially all of the water in the tank is hot, an auxiliary thermally-actuable heater control switch for deenergizing said heater when a predetermined fractional part of the water in the tank is hot, a plural-contact plural-position heater control switch normally yieldingly biased into one position, electric connections between said switches and said heater to cause energization of said heater when the switch is in its normal position and less than all of the water in the tank is hot, a second electric load circuit and an electromagnet carrying the current flowing in said second circuit and effective to move said plural-position switch into its other position when said second circuit is carrying a current of predetermined value to continue energization of said heater through said auxiliary thermal switch in case less than said predetermined fractional part of the water in the tank is hot and until more than said predetermined fractional part of the water in the tank is hot, reduction of the current in said second circuit to below said predetermined value causing return of the plural-position switch to its normal position and energization of the heater through said main thermally-

actuable switch in case less than all of the water in the tank is hot and until substantially all of the water in the tank is hot.

5. A water heating system for a hot water tank comprising a first circuit including an electric heater, a main thermal heater control switch effective to deenergize the heater when substantially all of the water in the tank is hot, an auxiliary thermal heater control switch effective to deenergize the heater when a certain fractional part of the water content of the tank is hot, a second circuit and electromagnetically

actuated switching means controlled by the current in said second circuit to cause said heater to be energized through said main thermal switch in case the value of the current in said second circuit is below a given value and said main thermal switch is subject to cold water and to cause said heater to be energized through said auxiliary thermal switch in case the value of the current in said second circuit is above said given value and said auxiliary thermal switch is subject to cold water.

CLARK M. OSTERHELD.
